UNITED STATES PATENT OFFICE.

THOMAS H. WALL, OF FITLER, MISSISSIPPI.

PACKAGE-TIE AND TEMPORARY BINDER.

1,238,720.

Specification of Letters Patent. Patented Aug. 28, 1917.

Application filed August 18, 1916. Serial No. 115,662.

To all whom it may concern:

Be it known that I, THOMAS H. WALL, a citizen of the United States, residing at Fitler, in the county of Issaquena and State 5 of Mississippi, have invented certain new and useful Improvements in Package-Ties and Temporary Binders; and I do hereby declare the following to be a full, clear, and exact description of the invention, such as 10 will enable others skilled in the art to which it appertains to make and use the same.

The invention relates to a combined package tie and temporary binder.

The object of the present invention is to 15 improve the construction of package ties and temporary binders and to provide a simple, practical and comparatively inexpensive device of strong and durable construction adapted for tying various kinds of packages 20 and binding magazines and other periodicals and capable of eliminating the use of rubber bands, cords and the like and of being quickly applied to and removed from a package or other object.

25 With these and other objects in view, the invention consists in the construction and novel combination of parts hereinafter fully described, illustrated in the accompanying drawing, and pointed out in the claims here- 30 to appended; it being understood that various changes in the form, proportion, size and minor details of construction, within the scope of the claims, may be resorted to without departing from the spirit or sacrificing 35 any of the advantages of the invention.

In the drawing

Figure 1 is a perspective view of a combined package tie and temporary binder constructed in accordance with this invention,

40 Fig. 2 is a longitudinal sectional view of the same,

Fig. 3 is a perspective view illustrating another form of the invention,

45 Fig. 4 is a plan view of the same.

Like numerals of reference designate corresponding parts in the several figures of the drawing.

In the accompanying drawing in which 50 is illustrated the preferred embodiment of the invention, the combined package tie and temporary binder comprises in its construction, a substantially oblong clamp and consists of a single strip or piece of spring metal or other suitable material bent to form sides 1 and 2, and ends 3 and 4. The ends

3 and 4 are straight and the sides are curved longitudinally and present inner convex faces to a package or other object and the convex engaging faces 5 are roughened to 60 prevent the device from slipping on a package or magazine. The device which is designed to be constructed in various sizes to adapt it to the character of the use for which it is intended, obviates the necessity of employing bands of rubber, cord and the like and the side 1 is provided with a ball 6 and terminates short of the end 3 which is provided with an arm or extension 7 having a substantially cylindrical keeper 8 disposed 70 transversely of the arm 7 and preferably opens at both sides and adapted to receive the ball 6 which may be introduced into and removed from the cylindrical keeper by moving the side 1 laterally in either direction. The cylindrical keeper is provided with a slot or opening extending the entire length of the keeper to receive the terminal portion of the side 1 adjacent the ball. By this construction, the ball which is arranged 75 at the free end of the side 1 may be readily engaged with and quickly disengaged from the said keeper. The side 1 is also provided adjacent to its free end with an exterior longitudinal rib 9 formed by denting or grooving the side from the inner face thereof and adapted to enable the said side to be readily engaged with the finger for moving the ball into and out of the keeper 8. The oblong resilient clamping device is adapted to be 80 quickly applied to a package of any desired character and it may also be employed for binding a plurality of magazines or other periodicals or the like and the resiliency of the sides will enable the device to engage 85 packages or other objects of varying thicknesses.

In Figs. 3 and 4 is illustrated another form of the invention in which the arm 10 of the side 11 is provided with a keeper 100 notch 12 and the curved side 13 has its free terminal 14 tapered and adapted to be readily sprung into and out of engagement with the said keeper notch 12. The side 13 is also provided with a rib 15.

105 The inwardly curved sides which connect the parallel ends of the device are adapted to be gradually expanded and they may, if necessary, be bowed outwardly to accommodate the package or magazines to which it 110 is to be applied and the fastening device in either form of the invention will securely

hold the free terminal of the adjacent side. In practice, the tapered terminal of the side 13 will be of sufficient length to prevent it from being accidentally withdrawn from 5 the notch by any outward bowing of the said side 13.

What is claimed is:—

1. A combined package tie and temporary binder of substantially oblong form constructed of a strip of resilient material bent to form substantially straight transverse ends and longitudinal sides, said sides being curved inwardly throughout the length of the device to present inner convex engaging faces which are adapted to be flexed in the opposite direction by the contents of the device, said engaging faces being roughened, and the terminals of the strip being located at one end of the device, one of the 20 terminals of the strip being provided with a keeper and the other terminal having a coacting portion detachably engaging the keeper.

2. A combined package tie and temporary binder constructed of a strip of resilient material and consisting of a substantially oblong clamp and comprising ends, and inwardly curved sides, one of the sides hav-

ing a free terminal portion provided with a ball and a substantially cylindrical keeper 30 extending across the strip detachably receiving the said ball and connected with and carried by the adjacent end of the device, said keeper permitting the ball to be introduced into it from either side. 35

3. A combined package tie and temporary binder comprising an oblong clamping frame composed of spaced sides and ends, one of the sides being provided with a free terminal portion having a ball, and an arm 40 extending from the adjacent end of the device and provided with a cylindrical keeper disposed transversely and open at each end to enable the ball to be introduced and removed from it at either side of the 45 device, said keeper being provided with a slot or opening extending from one end to the other of the keeper and receiving the said free terminal portion adjacent to the ball. 50

In testimony whereof I affix my signature in presence of two witnesses.

THOMAS H. WALL.
